UNITED STATES PATENT OFFICE

2,336,871

ELECTRIC SWITCH

John E. Lake, Schenectady, N. Y., assignor to
 General Electric Company, a corporation of
 New York

Application February 28, 1942, Serial No. 432,724

2 Claims. (Cl. 200—103)

My invention relates to electric switches, more particularly to electric switches of the type known as contactors, and has for its object a simple and reliable device of this character, the movable parts of which are constructed so as to balance impact forces and prevent circuit failure from shock.

In carrying out my invention in one form, I provide a switch arm which rotates about a stationary supporting pivot at its center and which is provided with one or more movable switch contacts at each end. For the operation of this switch arm, I provide a magnet coil having two aligned plunger type armatures each of which is connected to a bell crank arm or lever, the opposite ends of the levers being pivotally connected together. These bell cranks are mechanically connected through a link to the switch arm for operation of the switch arm to a closed circuit position when the magnet is energized.

For a more complete understanding of my invention, reference should be had to the accompanying drawing in which Fig. 1 is a plan view of an electric switch embodying my invention; Fig. 2 is a left-hand elevation view of Fig. 1; Fig. 3 is a sectional view taken along the line 3—3 of Fig. 1 and looking in the direction of the arrows; while Fig. 4 is a simplified view in perspective of the device shown in Figs. 1 to 3, inclusive.

Referring to the drawing, my invention in one form comprises a base plate or member 10 which may be made of metal and which forms a support for the various parts of the device. These parts comprise a contact arm 11 made of electrically insulating material and provided with a central pivotal support 12, a stationary contact and terminal support 13 made of electrically insulating material secured to the base adjacent the upper end of the contact arm as seen in Figs. 1, 2 and 3, a stationary contact and terminal support 14 also secured to the base adjacent the other end of the pivoted contact arm 11, and a magnet coil 15 between and operating bell cranks 16 and 17 which are connected to the switch arm 11. Thus the coil 15 operates to move the switch arm 11 about its pivot 12 between its open and closed circuit positions.

For the support of the stationary pivot rod 12, brackets 18 and 19 are provided at its opposite ends, which brackets are secured to the base by suitable screws 20 and 21. The bracket 19 furthermore extends under the magnet coil 15 and has an upper substantially horizontal portion 22 on which the coil is mounted. As shown, the coil is provided with a rectangular magnet frame

23, the outer side plates 24 and 25 of which are secured to the horizontal portion 22 by suitable screws 26 and 27.

Preferably, the contact arm 11 is loosely mounted on the pivot rod 12 so that it turns on the rod in moving between its closed and open circuit positions. It is held in a central position on the rod by means of compression springs 28 and 29 on opposite sides, the spring 28 being between the contact arm and the bracket 18, while spring 29 is between the contact arm and a clip 30 frictionally secured to the rod 12.

The contact arm 11, which together with the supports 13 and 14 is preferably made of a molded electrically insulating material such as a phenolic condensation product, is of irregular shape to provide for arc barriers between contacts and for convenience in the connection of the operating mechanism. At its upper end, as seen in Figs. 1 to 3, it carries two spring pressed bridging contacts 31 and 32 which are spaced apart and engage respectively pairs of stationary contacts 33 and 34 (one contact of the pair 34 not being shown) mounted on the support 13.

An arc barrier wall 35 formed integrally with the support 13 extends upward between the pairs of stationary contacts 33 and 34 and the upper end of the switch arm 11 has a curved or hood portion 36 between the movable bridging arms 31 and 32 and partially enclosing and encircling the barrier 35 when the contact arm is in its closed circuit position. This provides an arc path through the air of increased length between the bridging contacts when they are in the closed circuit position. It will be understood that these bridging contacts serve electrically to connect together the contacts of each of the pairs 33 and 34 and, therefore, the bridging contacts are connected to an electric circuit only after being moved toward their closed circuit positions.

At its other or lower end the contact arm 11 is provided with a third bridging contact 37 which, when the contact arm is moved counter-clockwise, as seen in Fig. 2, engages stationary contacts secured on the ends of electrically conducting supports 38 and 39 secured to the electrically insulating support 14. Also carried on this lower end of the contact arm is an interlock or control circuit bridging contact 40 which, when the contact arm is moved to its closed circuit position, engages two stationary contacts 41 and 42 mounted on the support 14. Also contacts 40, 41 and 42 can be assembled reversed with respect to the position shown so that they are normally closed when arm 11 is in the open

position shown, and open when arm 11 is in the closed circuit position.

This arrangement of one or more bridging contacts on each end of the pivoted arm 11 and the balancing of the arm 11 itself provide for a substantial balance of the contact arm and the parts mounted on it about the supporting pivot pin 12 whereby the contact arm assembly is substantially free from mechanical shocks and jars of translation applied to the support on 10 which the switch is mounted.

For the operation of the contact arm 11, the magnet coil 15 is provided with two aligned plunger armatures 43 and 44, these armatures extending substantially parallel with the base 10. 15 The outer ends of these armatures are pivotally connected respectively to the ends of the bell crank levers 16 and 17 pivotally mounted on the base 10. As shown, the bell crank lever 16 is pivotally mounted at its center on the pivot pin 12, while the bell crank lever 17 is pivoted at its center also on a pivot pin 45 (Fig. 2) secured to the bracket 19. Thus it will be observed that the arms of the bell cranks to which the armatures are attached extend upward from the base 20 in substantially parallel relation with each other, and substantially at right angles to the center line of the coil 15. The other two arms of the bell cranks extend toward each other into overlapping relation and they are connected pivotally together by pivot pin 46. Enough looseness in a radial direction is provided between the pin 46 and at least one of the bell cranks to permit sufficient pivotal movement of the bell cranks to move the plungers between their attracted and unattracted positions. One of the bell cranks, as shown the bell crank 17, is connected to the switch arm 11 by means of a link 47 having one end pivotally connected to the link 17 at the point 48 and the other end pivotally connected to the switch arm at the point 49.

A helical spring 50 is provided for biasing the contact arm to the open position shown. This spring surrounds a hub 51 on the contact arm 45 surrounding the pin 12. One end of the spring is secured to the base 10, while the other end 52 is secured to the switch arm so as to bias the switch arm to its open circuit position.

When the coil 15 is energized, the two plungers 43 and 44 are attracted toward each other and preferably engage each other at their inner ends. The two plungers are connected to each other through the pivot 46 and operate through the link 47 the contact arm to its closed circuit position.

It will be observed that the movable magnet operating parts, including the two plungers of identical construction and weight and the two identical bell cranks, provide a construction which is dynamically balanced with respect to shocks and jars of translation or straight line movement applied to the support on which the switch is mounted.

For example, a translational shock applied to the switch in a direction from top to bottom as viewed in Fig. 2, which force is applied directly to the supporting pivots 12 and 45, produces a force due to the inertia of the parts tending to turn the bell crank 16 in a counter-clockwise direction about the pivot 12. This same shock also produces a force tending to turn the bell crank 17 in a clockwise direction about the pivot 45. Since these two forces counteract each other at the pivot 46 and are equal, the tend-

ency of the bell cranks to turn is balanced out. Likewise equal and opposite forces are produced by a shock in the opposite direction.

The plunger type armatures 43 and 44 are 5 advantageous in eliminating rebound of the armatures from their attracted positions in the event of a shock. Thus an armature which in its attracted position is in solid abutting engagement with a cooperating magnet frame secured rigidly to a support, may be thrown from its attracted position against the pull of the magnet coil by a severe shock. This is because the shock is applied through the support directly to the stationary magnet frame and when transmitted by the magnet frame to the armature may throw the armature toward its unattracted position against the holding force of the magnet coil. In the arrangement I have disclosed, the two plunger type armatures engage each other at their 15 inner ends when in their attracted positions, and therefore do not abuttingly engage the magnet frame 23. Shocks applied to the magnet frame in the direction of movement of the plunger armatures, therefore, are not transmitted directly from the magnet frame to the plungers, and this rebound movement of one or the other of the plungers is avoided.

A translational shock applied to the switch from the left to the right, as viewed in Fig. 2, 20 does not produce forces tending to move the bell cranks to their open positions because of the fact that the bell cranks are damped by the much greater inertia forces of the plunger armatures 43 and 44 which are not free to move in that direction. This is true also of the force of a shock in the opposite direction. Also, a shock at right angles to the device, as seen in Fig. 2, does not produce any switch opening force because the parts are not free to move in that direction.

Also shown on the drawing are the various quickly detachable terminal connections for the stationary contacts. Thus the screw connections 53 and 54 lead respectively to the pair of stationary contacts 33, while in a similar manner the screw connections 55 and 56 lead respectively to the pair of contacts 34. Likewise, the stationary contact 41 is provided with a contact screw 57, the stationary contact 42 with a contact screw 58, and the supports 38 and 39 with contact screws 59 and 60.

It is contemplated that the electric switch disclosed will be used in a 3-phase supply circuit such as for the starting of a 3-phase electric motor. Thus the three pairs of main contacts 33, 34, 38 and 39 will be connected in the three supply lines to the electric motor. The auxiliary interlock bridging contact 40 will be connected in any suitable control circuit that may be desired, for example, to short-circuit a push button switch initially used to close the circuit of the coil 15.

The bridging contacts 31, 32 and 37 are suitably connected resiliently to the arm 11. The support for the bridging contact 31 will be described in detail, the supports for the other bridging contacts being the same. It consists of a U-shaped metal strap 61 whose arms are spaced apart a distance slightly greater than the width of the bridging contact 31 which is positioned between the sides and has its center normally seated on the cross portion of the strip 61 by a helical spring 62 encircling the member 61. Actually, the central portion of the bridging contact lying between the sides of the U-shaped

member is reduced in width, as clearly illustrated in Fig. 4, thereby to provide shoulders on each side of the U-shaped member which hold the bridging contact centrally on the U-shaped member.

The U-shaped member is secured to the arm 11 by passing its ends through a rectangular aperture 63 in the arm and by providing spaced apart projections 64 and 65 in each arm of the U-shaped member in position to embrace opposite sides of the edges of the aperture 63 thereby to hold the U-shaped member in position. Preferably, these projections 64 and 65 are made by striking out slight tabs of the metal of the arms. When the U-shaped member is put in position, two arms are pressed together somewhat, the member being made of resilient material so that the outer projection 65 in each arm passes through the aperture 63. Then the arms spring apart with the two opposite side walls of the aperture lying between the pairs of projections on the arms.

Preferably also, as seen in Fig. 2, the bridging contact 31, as well as the other bridging contacts, is positioned angularly with respect to its pair of stationary contacts 33 so that one end of the bridging member engages its stationary contact first and after relatively small angular movement of the arm 11 toward the closed circuit position. As shown, engagement is made first with the lowermost contact. This is of advantage during the opening movement in that the opening of the circuit and any arcing takes place at the upper contacts.

While I have shown a particular embodiment of my invention, it will be understood, of course, that I do not wish to be limited thereto since many modifications may be made, and I therefore contemplate by the appended claims to cover any such modifications as fall within the true spirit and scope of my invention.

What I claim as new and desire to secure by Letters Patent of the United States is:

1. An electric switch comprising two bell crank levers mounted on spaced apart stationary pivots with first arms of said levers extending toward

each other and second arms of said levers extending in substantially parallel relation with each other, a pivotal connection between said first arms, a magnet coil mounted between said second arms, a pair of plunger armatures extending into opposite ends of said coil connected to said second arms, said plunger armatures extending into opposite ends of said coil and having their inner ends in abutting engagement with each other when moved to their attracted positions upon energization of said coil, a switch arm pivotally mounted at its center, a link connecting said switch arm with one of said levers, and a spring for biasing said switch arm about its pivot to open circuit position whereby said armatures are biased apart to unattracted positions and upon energization of said coil said armatures are pulled toward each other and said switch arm thereby turned to its closed circuit position.

2. An electric switch comprising two bell crank levers mounted on spaced apart stationary pivots with first arms of said levers extending toward each other and second arms of said levers extending in substantially parallel relation with each other, a pivotal connection between the ends of said first arms, a magnet coil mounted between said second arms, a pair of plunger armatures in said coil having their outer ends pivotally connected to the ends of said second arms, a switch arm mounted at its center on a stationary pivot, a switch contact carried on each end of said arm, said plunger armatures extending into opposite ends of said coil and having their inner ends in abutting engagement with each other when moved to their attracted positions upon energization of said coil, a link connecting said switch arm with one of said levers, and a spring for biasing said switch arm about its pivot to open circuit position whereby said plunger armatures are biased apart to unattracted positions and upon energization of said coil said plunger armatures are pulled toward each other thereby to turn said switch arm to its closed circuit position.

45

JOHN E. LAKE.
